CLAIM

The ornamental design for a display screen or portion thereof with transitional graphical user interface for displaying elevator information as shown and described.

DESCRIPTION

FIG. 1 is a first image in a sequence for a display screen or portion thereof with transitional graphical user interface for displaying elevator information, showing our new design in a first embodiment including an elevator environment;

FIG. 2 is a second image in a sequence thereof;

FIG. 3 is a third image in a sequence thereof;

FIG. 4 is a first image in a sequence for a display screen or portion thereof with transitional graphical user interface for displaying elevator information, showing our new design in a second embodiment;

FIG. 5 is a first image in a sequence thereof; and,

FIG. 6 is a second image in a sequence thereof.

The appearance of the transitional user interface sequentially transitions between the images shown in FIGS. 1-3 and 4-6. The process or period in which one image transitions to another forms no part of the claimed design. The broken lines showing the environment, display screen or portion thereof, and/or portions of the graphical user interface form no part of the claimed design.
